CLAIM

The ornamental design for a floor mat, as shown and described.

DESCRIPTION

FIG. 1 is a top view of a floor mat showing my new design; FIG. 2 is a rear view of the floor mat shown in FIG. 1; FIG. 3 is an enlarged left side view of the floor mat shown in FIG. 1 in inverted condition and broken in two halves for ease of illustration;

FIG. 4 is an enlarged right side view of the floor mat shown in FIG. 1 and broken in two halves for ease of illustration; FIG. 5 is an enlarged end view of the floor mat shown in FIG. 1 in inverted condition;

FIG. 6 is an enlarged end view opposite the end view shown in FIG. 5 of the floor mat shown in FIG. 1; and, FIG. 7 is a perspective view of the floor mat shown in FIG. 1 at a reduced scale.
